United States Patent Office

Des. 216,225
Patented Dec. 2, 1969

216,225

FILM CARTRIDGE

Walter Daniel Grupp, Boulder, Colo., assignor to Elba Systems Corporation, Denver, Colo., a corporation of Colorado

Filed Nov. 6, 1968, Ser. No. 14,336

Term of patent 14 years

Int. Cl. D16—99

U.S. Cl. D61—1

FIG. 1

FIG. 2

FIG. 3

FIG. 4

FIG. 5

FIG. 6

FIGURE 1 is a front elevational view of a film cartridge, showing my new design;

FIGURE 2 is a rear elevational view of the film cartridge shown in FIGURE 1;

FIGURE 3 is a left end elevational view of the film cartridge shown in FIGURE 1;

FIGURE 4 is a right end elevational view of the film cartridge shown in FIGURE 1;

FIGURE 5 is a top plan view of the film cartridge shown in FIGURE 2; and

FIGURE 6 is a bottom plan view of the film cartridge shown in FIGURE 2.

I claim:

The ornamental design for a film cartridge, as shown.
